R. E. BREWER

LIQUID FUEL VAPORIZATION

Filed June 16, 1921

UNITED STATES PATENT OFFICE.

ROBERT E. BREWER, OF BOSTON, MASSACHUSETTS, ASSIGNOR TO BUTLER AMES, OF LOWELL, MASSACHUSETTS.

LIQUID-FUEL VAPORIZATION.

Application filed June 16, 1921. Serial No. 478,074.

My invention relates to that general class of carburetors which employs volatile or vaporizable liquid fuel, and has for its fundamental object the automatic regulation of the proportions of air and fuel inducted to the internal combustion engine; a regulation which preserves a predetermined proportion between air and fuel, affected but little if at all by variations in external conditions such as atmospheric pressure, and which is conditioned primarily on transforming the fuel into its gaseous condition before it is subjected to the regulative operation of the fuel gas measuring factors of the carburetor.

When both ingredients destined to produce the combustible mixture are in the condition of gas, the same laws of flow through orifices and ducts apply to both, and gas flow factors may be so applied—according to my invention,—that predetermined weights of gaseous fuel and of air, passing per unit of time into the duct or chamber where they mingle, are regulated, with substantial accuracy, and the proportion of the two ingredients held under control.

All carburetors which function by delivering fuel in the liquid—albeit finely divided—condition to the moving column of air in which eventually the fuel is to be vaporized labor under the disadvantage due to the relatively great density of the fuel in its liquid condition. Regulation of the weight of the fuel gas ultimately produced, by initial regulation of the delivery of the same fuel in liquid form, is impossible to achieve with any approach to accuracy or delicacy, since the minutest globule of the liquid fuel expands enormously in passing to the gaseous state. Many carburetors have been designed with provisions for converting liquid fuel into gas before its mixture with the column, but none, so far as I am informed, which utilize the vapor pressure, incidental to the conversion, to regulate automatically the weight of liquid fuel inducted into the vaporizer, and at the same time automatically regulate the flow of fuel gas from the vaporizer to the air column. The manner in which these regulatively coacting factors operate is characteristic of my invention, and will be further explained in association with the description of a carburetor of which the drawings hereto annexed are illustrative.

In these drawings,

Fig. 1 is a vertical section showing all the essential parts of the carburetor.

Fig. 2 is a horizontal section, taken at the line 2—2 of Fig. 1;

Fig. 3 is a section on line 3—3 of Fig. 4; and

Fig. 4 is a view in elevation, much enlarged, of a part of the liquid fuel induct.

B represents a receptacle for vaporizable liquid fuel, which may be of the spontaneously vaporizing type, such as gasoline, or a heavier and less volatile liquid fuel. As illustrated, this receptacle is shown as of the float-valve variety, containing a float 2, but its specific character is immaterial.

P is a tube, open to the atmosphere at one end, and terminating inside a second tube P'; these two forming a continuous duct from the atmosphere to the vaporizer G. The vaporizer may have longitudinal ribs 6 on the inside and circumferential ribs 7 on the outside as shown in Fig. 1. At p the tube P is constricted so as to form a venturi, and at L is perforated or slotted, to provide an inlet for liquid fuel. The perforation L is located at or near the point of minimum pressure in the venturi p. The tube P' and the portion of tube P above inlet L constitute a liquid-fuel duct leading to the vaporizer G.

To provide means for raising liquid fuel from the supply in the receptacle B, a tubular skirt 5 surrounds the housing 1 of the tube P; this housing is apertured at 4 to give access to the perforation L. It should be noted that the opening 3 which may be used to introduce highly volatile fuel when it is necessary to prime the vaporizing carburetor, is normally closed.

It will be understood, that when a fall in pressure in the vaporizer G produces air flow from the outer atmosphere through the duct P, P', the low pressure supervening at the throat of the venturi p will cause the liquid fuel to rise inside the skirt 5 and enter the tube P at L. The rapidly moving air column in the tube P acts as an aspirator which draws the liquid fuel from within the skirt 5, breaking the liquid fuel into small globules, and carries it into the vaporizer G. This air column in the tubes P, P', functions essentially as a vehicle to convey fuel in liquid form to the vaporizer. While

the air thus inducted into the vaporizer with the liquid fuel to some extent modifies the constitution of the gas or vapor therein formed, its quantity is preferably as small as is consistent with performance of the fuel-vehicle function, and is insufficient to affect the principle of operation of the carburetor, which comprises the formation and maintenance of fuel in gaseous form, with substantially no air in mixture, as a reservoir from which to draw fuel gas into a moving air column, so that the flow of both air and fuel are independently regulated as gases, and their proportions thus controlled.

15 The pressure-differential responsible for fall in pressure in the vaporizer G below that of the atmosphere is produced by the operation of the venturi V, formed in the main air column tube or air duct D, which by 20 continuation becomes the mixing tube or combustible mixture duct M, leading to the engine or generically equivalent apparatus supplied by the carburetor. The inlet end A of this air tube contains the regulating and 25 constricting valves T and C, presently to be described.

A branch duct F which enters the venturi V at or near its point of minimum static pressure, connects the vaporizer G with the 30 main air duct. The effective cross-section of this branch duct F is determined by the position of the rotatable plate-valve R, which is secured to the end of tube P' as to a stem. The tube P' is mounted to rotate on its axis; an externally accessible crank T', secured to the tube P', supplies means for rotatably changing the position of the tube P' and with it the plate-valve R. Thus the crank T' and its operating 40 connections constitute means for conjointly controlling the air valve or regulator T and the vapor valve R. The orifice R' in the plate valve R is tapered in form as shown in Fig. 2, so that the effective cross-sectional 45 area of the branch duct F may be varied.

Attention is now drawn to the fact that the minimum pressure determinant at the neck of the venturi V is the factor operating alike to induce air flow from the atmosphere 50 through the inlet A, and gas flow from the vaporizer G. While the pressure in the vaporizer G is lower than that of the atmosphere, the differential will not be very great while the demand on the carburetor 55 remains constant.

The liquid fuel inducted into the vaporizer G is there converted into gas by the application of heat. This may be conveniently accomplished in the manner usual with liquid 60 fuel vaporizers employed with internal combustion engines, that is by placing the vaporizer inside a chamber H, which is connected with, or forms part of, the exhaust pipe of the engine.

65 While I do not regard it as essential, it has

nevertheless been found desirable to provide for variations in the size of the liquid fuel inlet L, to keep pace, roughly, with variations in the freedom of air passage in the inlet A and of gas flow through the variable valve-aperture R'. For this purpose the lower end of the tube P' is cut away on one side, leaving a half cylinder p' which, as the tube P' is rotated, uncovers more or less of the aperture L. This is illustrated in Figs. 75 3 and 4.

On the outside of the tube P', in the air inlet A, there is secured the air supply regulating valve T. The independent choke valve C, also in the air inlet A, may be used 80 to produce special regulation of air supply, and ordinarily will not be moved from the setting which has been determined on as proper for the particular fuel used, or the general atmospheric condition.

85 The operation of the carburetor, above structurally described, is as follows: Assume the valves p', T, and R to be at their positions of widest opening (as shown in Fig. 1) and the engine running under full load and 90 at constant speed. The minimum pressure at the throat of the venturi V determines the pressure differentials which respectively cause air flow into the inlet A and gas flow into the branch duct F. The flow of air, 95 with its burden of liquid fuel, through the duct P, P', is determined by the pressure differential between the interior of the vaporizer G and the atmosphere. The liquid fuel, vaporized by the heat applied to the 100 vaporizer G, produces or assumes a vapor pressure, which operates as a back pressure, or rather reduces the value of the pressure differential as between the interior of the vaporizer and the atmosphere, 105 below the value represented by the pressure differential as between the venturi V and the atmosphere. The effect is to produce a condition of balance between demand and supply, and thus to maintain a 110 substantially constant pressure in the vaporizer G. Therefore, the minimum static pressure at the throat of the venturi V, 115 draws air from a source at constant pressure (atmospheric) and gas from a source at constant pressure (a little below atmospheric, in the vaporizer). The areas of the 120 ducts for admission of air and gas, respectively, being for the time fixed, the same laws of flow obtain for both ingredients of the final mixture, both being gases, and the proportion of these ingredients will be constant.

125 The automatic regulation of liquid fuel flow into the apparatus will perhaps be more clearly understood by a description of the behavior of a carburetor possessing such functionally related factors as are above described, when the engine which it feeds is being started, and all parts are cold.

As the engine is turned and draws air through the air supply pipe A, since the vaporizer G is cold, little or no fuel evaporation takes place in it. The differential of pressure then effective to induce flow into and through the duct P, P' is, substantially, that between the pressure at the venturi V and the atmosphere. The small size of the duct P, P' produces a rapid flow of air 10 through it, and the static pressure at the throat of the venturi p falls to a correspondingly low value, inducing a copious flow of liquid fuel through the aperture L. If the engine is to be run on a relatively heavy 15 and slowly volatile fuel eventually, a highly volatile fuel should be supplied at starting, through the priming passage 3. The engine will be supplied, at the start, with a rich mixture of fuel and air, which is precisely 20 as it should be.

Then the engine starts, and before the exhaust gases have heated the vaporizer G, the supply of rich mixture goes directly to the engine; the conditions being there much 25 as when the usual type of gasoline carburetors is employed. Presently, however, the vaporizer G becomes hot, the liquid fuel entering it is vaporized, and exerts its vapor pressure, producing a reduced pressure- 30 differential as between the interior of the vaporizer and the outer atmosphere; this reduction in pressure differential reduces the speed of the air column in the duct P, P', and therefore the indraft of liquid fuel 35 through the aperture L. This repression of the air column which serves as the vehicle for liquid fuel progresses until a balance has been automatically reached.

Variations in condition, as by variation 40 of position of the valves p', T and R, are responded to be similar self-adjustment of pressure-differentials in the apparatus. If the external atmospheric pressure varies, as when the altitude of the apparatus is 45 changed, the differential relationships in the carburetor do not alter in proportion to the barometric change, but on the contrary remain substantially the same, unless the altitude changes be very great, as is often 50 the case in an ascending or descending airplane.

With the liquid fuel introduced into the small air duct P, as above described, the liquid fuel is sprayed into the vaporizer 55 with considerable velocity and is distributed throughout the vaporizer, thereby subjecting all the fuel to approximately the same temperature and at the same time drawing heat uniformly from the entire area of the vaporizer chamber so that no part of the chamber becomes overheated to such extent as to crack the portion of fuel coming in contact therewith.

I claim:

1. In a combined oil vaporizer and carbureter, a combustible-mixture duct, an air duct, leading thereto from the outer atmosphere, a substantially closed vaporizing chamber, separate from the combustible-mixture duct, a vapor duct leading from 70 said chamber into the air duct, an air and fuel duct independent of said air duct, leading into the chamber from the outer atmosphere and adapted to carry a stream of air therethrough, and means for admitting fuel into the air stream in said air and fuel duct and spraying the same into said vaporizing chamber.

2. In a combined oil vaporizer and carbureter, a combustible-mixture duct, an air duct leading thereto from the outer atmosphere and provided with a constriction adapted locally to reduce static pressure in an air column moving therethrough, a closed vaporizing chamber, separate from 75 the combustible mixture duct, a vapor duct leading from the chamber into the air duct at its constriction, an air and fuel duct, independent of said air duct, leading into the chamber, and adapted to conduct a stream of air therethrough, and means for aspirating and spraying fuel through said air and fuel duct into said vaporizing chamber.

3. In a combined oil vaporizer and carbureter, a combustible-mixture duct, an air duct leading thereto from the outer atmosphere, a closed vaporizing chamber, separate from the combustible-mixture duct, a vapor duct leading from the chamber into the air duct and comprising an aspirating vapor-orifice an air and fuel duct independent of said air duct, leading into the chamber from the outer atmosphere and adapted to conduct a stream of air therethrough, and means for introducing fuel into the air stream in said air and fuel duct.

4. In a combined oil vaporizer and carbureter, a combustible-mixture duct, an air duct leading thereto from the outer atmosphere and provided with a constriction adapted locally to reduce static pressure in an air column moving therethrough, a closed vaporizing chamber, separate from the combustible-mixture duct, a vapor duct leading from 110 the chamber into the main air duct at its constriction, comprising an aspirating vapor-orifice and means for controlling the flow of vapor therethrough, an air and fuel duct independent of said air duct, leading into the chamber from the outer atmosphere and adapted to conduct a stream of air therethrough, and means for introducing fuel into said air stream.

5. In a combined oil vaporizer and carbureter, a combustible-mixture duct, a main air duct leading thereto from the outer atmosphere and provided with a constriction adapted locally to reduce static pressure in an air column moving therethrough, a sub- 115 120 125

130

- stantially closed vaporizing chamber, separate from the combustible-mixture duct, a vapor duct leading from the chamber into the air duct at its constricted region, an air and fuel duct, independent of said air duct, leading into the chamber from the outer atmosphere and adapted to conduct a stream of air therethrough, means for introducing fuel into said air stream, means for controlling the flow of vapor through said vapor duct, and means in said air duct to vary its effective cross-section.
6. In a combined oil vaporizer and carbureter, a combustible-mixture duct and an air duct leading thereto from the outer atmosphere, a substantially closed vaporizing chamber, separate from the combustible-mixture duct, a vapor-duct leading from the vaporizing chamber into the air duct, an air and fuel duct independent of said air duct, leading into said chamber from the outer atmosphere, means between the chamber and the outer atmosphere in said air and fuel duct to introduce liquid fuel into said chamber, and means to vary proportionately the effective cross-section of said air duct and of said vapor duct.
7. In a combined oil vaporizer and carbureter, a combustible-mixture duct, an air duct leading thereto from the outer atmosphere and provided with a constriction adapted locally to reduce static pressure in an air column moving therethrough, a substantially closed vaporizing chamber, separate from said combustible-mixture duct, a vapor duct leading from the vaporizing chamber into the main air duct at its constricted region, an air and fuel duct independent of said air duct, leading into said chamber from the outer atmosphere and adapted to conduct a stream of air there-
- through, means in said air and fuel duct for aspirating and spraying liquid fuel into said chamber, and means to vary the effective cross-section of said air duct and said fuel supply means.
8. In a combined oil vaporizer and carbureter, a combustible-mixture duct, a main air duct leading thereto from the outer atmosphere and provided with a constricted zone adapted locally to reduce static pressure in an air column moving therethrough, a substantially closed vaporizing chamber, a vapor duct leading from the chamber into the main air duct at its constricted region, a relatively small air and fuel duct, independent of said main air duct, leading into said chamber from the outer atmosphere and adapted to conduct a stream of air therethrough and thereby to aspirate liquid fuel into the chamber, and means to vary the effective cross-section of said air duct, said air and fuel duct, and of the vapor duct.
9. In a combined oil vaporizer and carbureter, a combustible-mixture duct, a main air duct leading thereto from the outer atmosphere, a substantially closed vaporizing chamber, a vapor duct leading from the chamber into the main air duct, an air and fuel duct leading to said chamber from the outer atmosphere and adapted to conduct a stream of air therethrough, aspirating means for spraying liquid fuel into said air stream and thence to said chamber, and means for conjointly controlling the fuel supply and flow of air and vapor through said air and fuel duct and vapor duct, respectively, with respect to the air stream in the main air duct.
